ATTORNEY.

UNITED STATES PATENT OFFICE.

JOSEPH JOHNSON, OF NEW YORK, N. Y.

CURRENT-RECTIFYING SYSTEM.

Application filed April 4, 1925. Serial No. 20,762.

To all whom it may concern:

Be it known that I, JOSEPH JOHNSON, a citizen of the United States, residing at New York city, in the county of Bronx and State 5 of New York, have invented certain new and useful Improvements in Current-Rectifying Systems, of which the following is a full, clear, and exact description.

My invention relates generally to systems 10 for modifying electric currents and relates particularly to current rectifying systems of the type adapted to rectify commercial alternating current and then to modify the pulsating rectified current for the purpose 15 of providing an unpulsating or uniform direct current. My invention relates more particularly to such systems which are adapted for use in connection with radio receiving sets for supplying current to the 20 plate circuits of the electron tubes, and commonly commercially known as B-battery eliminators, although it is to be understood that the system of my invention is adapted to other uses.

25 Heretofore such rectifying systems have not been entirely satisfactory. Commonly the direct current delivered thereby to the radio set has been sufficiently pulsating or undulatory in character as to cause an objectionable hum in the telephones or loud 30 speaker. Also commonly these systems have been incapable of impressing a sufficiently high voltage upon the plates of the amplifying tubes for their most effective operation.

35 Also when, as occasionally occurs, there is a momentary variation or drop in voltage in the commercial current, commonly these systems have passed on this variation or drop to the receiving set, resulting in a corresponding fading of the signal. Furthermore, 40 these rectifying systems have commonly been comparatively complicated, have required specially designed parts, and consequently have been expensive to manufacture.

45 Objects of my invention are to overcome the above noted objections and to produce a current rectifying system which will deliver a substantially uniform direct current of proper high voltage, so that the tubes will operate effectively and without noise so far as the voltages impressed upon their plates are concerned. Other objects of my invention are to produce a system for this purpose in the form of a compact, convenient and dependable apparatus, which is simple

in construction, which embodies readily replaceable standard parts, and which is inexpensive to manufacture. Other more particular objects and advantages of my invention will hereinafter appear.

50 My invention includes features of construction and combinations of parts as will appear from the following description.

I shall now describe the embodiment of 65 my invention illustrated in the accompanying drawing and shall thereafter point out my invention in claims.

The drawing is a diagrammatic representation of the operating parts and circuits 70 of an embodiment of my invention.

75 As illustrated in the drawing, a pair of terminals 1 and 2 are provided as means for establishing a connection to a commercial alternating current supply circuit. These terminals may be ordinary binding posts, or any other convenient means to which a usual two-wire cord may be connected and plugged into an electric light socket or wall socket. The commercial alternating current 80 to be supplied to the terminals 1 and 2 is most commonly 110 volts, at 60 cycles per second, as indicated on the drawing. A pair of line conductors 3 and 4 lead from the 85 respective terminals 1 and 2 and are connected to the ends of the primary 5 of a step-up transformer 6 having a double or two-part secondary 7.

90 The ends of the secondary 7 are respectively connected by conductors 8 and 9 to the plates of two rectifying tubes 10 and 11 of the heated filament type. The voltage impressed upon the plates of the rectifying tubes 10 and 11 by the step-up transformer 95 6 may be whatever desired, for example, 300 100 volts, and in the particular apparatus illustrated in the drawing as an embodiment of the system of my invention that has been found to be a suitable voltage. The transformer 6 may be of a usual standard commercial type, such as is commonly known as 105 an audio transformer.

110 Alternating current of the proper voltage, for example, six volts, is supplied to the filaments of the rectifying tubes 10 and 11, these filaments being connected in parallel in the filament-heating circuit. For thus heating the filaments a step-down transformer 12 has its primary 13 connected across the line conductors 3 and 4 by means of conductors 14 and 15. The ends of the secondary 16 of the step-down transformer 12 are respec-

tively connected by conductors 17 and 18 to conductors 19 and 20 which connect together the filaments of the tubes 10 and 11, so that these filaments are thereby connected in 5 parallel in an alternating current circuit. The step-down transformer 12 may be of the standard commercial type known as a bell transformer.

The rectifying tubes 10 and 11 may be of 10 the three-electrode type with the plate and grid of each tube connected together to form a single electrode element; and these tubes may conveniently be usual amplifying tubes of the "A" type, such as 201-A or 301-A.

15 Thus no special rectifying tubes are required, but the same type of tubes that are used in the radio set may also be employed as rectifiers. I have found that rectifying tubes without a filament such as sodium

20 tubes, commercially known as "S" tubes, cut down the plate circuit voltage too much to be desirable as rectifying tubes in a B-battery eliminator.

A positive lead 21 for rectified current is 25 connected to one side of the filament circuit, for example, to one of the filament-connecting conductors 19 or 20, and is shown as connected to the conductor 20. The other or outer end of the positive lead 21 is connected

30 to an output terminal 22, which may be a binding post or other convenient means for making a connection to the radio set. A negative lead or return lead 23 for the direct

35 rectified current is connected at its outer end to a terminal 24 through which it may be conveniently connected to the radio set, and at its inner end the negative lead 23 is connected to the middle point of the double

40 secondary 7 of the step-up transformer 6.

45 Current modifying means forming a feature of my invention are provided for effectively changing the pulsating rectified current to a substantially uniform direct current, free from noise-producing pulsations or undulations, such means also operating so as effectively to eliminate momentary current fluctuations, such as would cause a momentary fading, as will herein-after appear. A reactor 25 is connected in

50 series in the negative lead 23, and two storage devices shown as electrolytic condensers 26 and 27 are connected in parallel across the leads 21 and 23, the connections of the negative sides or terminals of these condensers to the negative lead 23 being made

55 at opposite sides of the reactor 25, separately for each condenser, by means of independent conductors 28 and 29 respectively, while the other or positive terminals of the condensers are shown as respectively connected to the positive lead 21 by means of separate

60 conductors 30 and 31, although obviously the connection to the positive lead could as well be made by means of a single conductor common to the two condensers if so desired.

The reactor 25 should have large inductance and is provided with an iron core, and the electrolytic condensers 26 and 27 are of large capacity. I have found an inductance of ten henries in the reactor 25 to be suitable, and electrolytic condensers such as 26 and 27 each having a capacity of twenty-eight microfarads have proved satisfactory. The reactor 25 may be of a readily purchasable commercial type and, in fact, I have found 75 that a bell transformer similar to the step-down transformer 12, when suitably connected in the negative lead 23, serves the purpose very well. The electrolytic condensers 26 and 27 may be of a commercial type and 80 may, for example, be of the general type of that disclosed in the patent to Mershon, No. 1,141,402, dated June 1, 1915.

By reason of employing filament type 85 rectifying tubes, such as 10 and 11, connected in the rectifying and filament-heating circuits as hereinbefore described, in carrying out my invention, a suitable plate voltage for the radio set can be obtained at the 90 positive terminal 22 with an economical consumption of the commercial alternating current. Most commonly it is desirable to impress ninety volts upon the plates of the amplifying tubes in the usual radio receiving set, and substantially uniform direct current 95 of that voltage may be taken from the positive terminal 22.

Less voltage is of course required for the 100 plate circuit of the detector tube, and the current for this purpose may be taken from a third positive terminal 32 connected by a branch lead 33 to the main positive lead 21 beyond the last condenser connection 31 or adjacent the terminal 22, a variable resistor 105 34 being included in the branch lead 33. The voltage most commonly desired for the plate of the detector tube is about twenty-two and one-half volts, but this may be varied by means of the variable resistor 34. 110 The resistor 34 may conveniently be of the compression type, so as thereby, in a resistor of small size, to obtain a sufficiently high resistance together with ample range of voltage adjustment, and this resistor may be of 115 a standard commercial type.

120 Electrolytic storage devices, such as the electrolytic condensers 26 and 27, perform a unique function and operate in a peculiarly effective manner in carrying out my invention. Such condensers are comparatively small in size while at the same time they have very large capacity. Furthermore, and of particular importance in carrying out my invention, these condensers are comparatively slow acting in the sense that they will not completely discharge substantially instantaneously, but will retain a considerable portion of their charge which they deliver comparatively gradually over an appreciable period of time. Therefore, as embodied 125 130

in my invention, such condensers are not only an important factor in substantially and effectively eliminating the pulsations from the original direct rectified current, so as to produce a substantially uniform and noiseless direct current, but I have found that also they effectively eliminate substantially momentary variations in the current, due to a momentary drop in voltage or other variation in the original commercial alternating current supplied through the line conductors 3 and 4. Under such circumstances the electrolytic condensers 26 and 27 deliver comparatively gradually a portion of their large charge, substantially in a manner similar to a battery, and thus serve for the required short period of time as a source of current for effectively keeping up the plate current and voltage, so that the volume of the reception in the receiving set is kept up without noticeable fading, such as commonly occurs.

I have found it impracticable in carrying out my invention to make use of ordinary or non-electrolytic radio condensers, because, in order to obtain the large capacity I have found to be most effective, the size of such condensers and the space taken up thereby would be prohibitive; and also I have found that such condensers do not operate so effectively for my purpose and particularly they do not effectually eliminate momentary variations or fluctuations in the current, probably because of their tendency to discharge, to whatever extent permitted, substantially instantaneously.

It is understood of course that the rectifying tubes 10 and 11 act alternately for rectifying both sides of the alternating current wave, so as to produce a substantially uninterrupted pulsating direct current, as is well known in the use of two rectifying tubes. However, I have found the operation of the current modifying means, including the reactor 25 and the electrolytic condensers 26 and 27, to be so effective that it is possible to omit one of the rectifying tubes; and the above noted modifying means will effectively convert the intermittent direct rectified current into a current of such uniformity that no hum results in the receiver, and there is no noticeable decrease in volume. In such case I have noted that the single rectifying tube appears to do double duty and it will not last so long, and it is preferred to employ the two tubes 10 and 11 as hereinbefore described.

While electrolytic condensers have been shown and hereinbefore described as employed in the illustrated embodiment of my invention, it is to be understood that within the broader scope of my invention, other electrolytic storage devices, which need not necessarily be condensers, may be employed, it being noted in this connection that the

polarity of the terminals of the condensers 26 and 27 is never changed. For example, suitable storage batteries might be employed. Also other forms of storage devices, such as the well known aluminum electrolytic cells. However, I prefer to employ, as storage devices, electrolytic condensers, such as the condensers 26 and 27. These condensers not only operate very effectively for the purpose desired in my invention, but they require no attention whatsoever, emit no gases and do not overflow. Also such condensers of suitably large capacity are of comparatively small size, and they are of a standard, readily obtainable commercial type. It may be noted that in their commercial form these condensers are completely enclosed and not open at the top as shown diagrammatically in the drawing, for the condensers 26 and 27.

The current rectifying and modifying system of my invention is adapted for use for any purpose where it is desired to obtain a uniform direct current from an alternating current source of supply. In using this system in connection with a radio set the terminals 22, 32 and 24 are to be connected to the set in precisely the same manner as a usual B-battery would be connected. The system of my invention is adapted to be used with the majority of the various types of radio receiving sets, for supplying "B" current to the plate circuits thereof.

It is to be noted that the system of my invention comprises relatively few parts of comparatively small size and that the circuit arrangement is simple. All of the several standard parts may be conveniently assembled and mounted and all circuit connections may be made by means of ordinary binding posts or other similarly readily connecting and disconnecting means. All parts and circuits may be readily assembled into a compact self-contained apparatus, and such an assembly has been made upon a base board and attached upright panel each seven by nine inches, which may be enclosed to form a box or cabinet, the entire apparatus occupying substantially no more space than a usual B-battery. If desired the entire system may be built directly into the radio set as a feature thereof, thereby further economizing space.

It is obvious that various modifications, changes in details, and variations in the arrangement of parts and connections, may be made in the system shown in the drawing and above particularly described within the principle and scope of my invention as pointed out in the appended claims.

I claim:

1. A current rectifying system comprising a source of alternating current, a step-up transformer connected to said source, a rectifying tube of the heated filament type hav-

ing its plate connected to said transformer, a step-down transformer connected to said source, a filament-heating circuit including the step-down transformer, a positive lead 5 for rectified current connected to the filament circuit, a negative lead for rectified current connected to the step-up transformer, a reactor connected in series in said negative lead, and two electrolytic storage devices 10 connected across said leads in parallel and connected to the negative lead at opposite sides of the reactor.

2. A current rectifying system comprising a source of alternating current, a step-up 15 transformer having a double secondary and having its primary connected to said source, two rectifying tubes of the heated filament type having their plates connected respectively to the ends of said secondary, a negative 20 lead for rectified current connected to the middle point of said secondary, a step-down transformer connected to said source, a filament-heating circuit including the step-down transformer and in which the filaments 25 of said tubes are connected in parallel, a positive lead for rectified current connected to one side of the filament circuit, a reactor connected in series in said negative lead, and two electrolytic storage devices connected 30 across said leads in parallel and connected to the negative lead at opposite sides of the reactor.

3. A current rectifying system comprising line conductors for commercial alternating current, a step-up transformer having its primary connected to said line conductors, a rectifying tube of the heated filament type having its plate connected to the secondary of said transformer, a negative 40 lead for rectified current also connected to said secondary, a step-down transformer having its primary connected across said line conductors, a filament-heating circuit including the secondary of the step-down 45 transformer, a positive lead for rectified current connected to the filament circuit, a reactor connected in series in the negative lead, and two electrolytic condensers connected in parallel across said leads and being connected 50 respectively at opposite sides of the reactor in the negative lead.

4. A current rectifying system comprising line conductors for commercial alternating current, a step-up transformer having its primary connected to the line conductors and having a double secondary, two rectifying tubes of the heated filament type one of 55 which has its plate connected to one of the parts of the double secondary and the other 60 of which has its plate connected to the other part of said secondary, a negative lead for rectified current connected to the middle point of said secondary, a step-down transformer having its primary connected across 65 the line conductors, a filament-heating cir-

cuit including the secondary of the step-down transformer and in which the filaments of the tubes are connected in parallel, a positive lead for rectified current connected to one side of the filament circuit, 70 a reactor connected in series in the negative lead, and two electrolytic condensers connected in parallel across said leads and being respectively connected to the negative lead at opposite sides of the reactor. 75

5. A current rectifying system comprising a source of alternating current, a rectifying device connected to said source, a lead for direct rectified current connected to said device, a return lead for the direct rectified current, a reactor connected in series in the negative lead, and two electrolytic storage devices connected in parallel across said leads and being respectively connected to the negative lead at opposite sides of the reactor. 80

6. A current rectifying system comprising a source of alternating current, a rectifying device connected to said source, a positive lead for direct rectified current connected to said device, a negative return lead for the direct rectified current, a reactor connected in series in the negative lead, and two electrolytic condensers connected in parallel across said leads and being respectively connected to the negative lead at opposite sides 95 of the reactor.

7. A current rectifying system comprising line conductors for commercial alternating current, a step-up transformer having its primary connected to the line conductors, a rectifying device connected to the secondary of said transformer, a positive lead for direct rectified current connected to said device, a negative lead for direct rectified current connected to said secondary, a reactor connected in series in the negative lead, and two electrolytic condensers connected in parallel across said leads and being respectively connected to the negative lead at opposite sides 100 of the reactor.

8. A system for modifying electric currents comprising a source of direct current having positive and negative leads, a reactor connected in series in one of said leads, and two electrolytic storage devices connected in parallel across said leads and being respectively connected to the reactor-containing lead at opposite sides of the reactor. 110

9. A system for modifying electric currents comprising a source of direct current having positive and negative leads, a reactor connected in series in the negative lead, and two electrolytic condensers connected in parallel across said leads and being respectively connected to the negative lead at opposite sides of the reactor. 120

In witness whereof, I hereunto subscribe my signature.

JOSEPH JOHNSON.
